UNITED STATES PATENT OFFICE.

JOHN CALDWELL, OF MINNEAPOLIS, MINNESOTA, ASSIGNOR TO THE W. S. NOTT COMPANY, OF MINNEAPOLIS, MINNESOTA, A CORPORATION.

LEATHER-STRETCHING DEVICE.

SPECIFICATION forming part of Letters Patent No. 699,833, dated May 13, 1902.

Original application filed January 25, 1900, Serial No. 1,424. Divided and this application filed January 8, 1901. Serial No. 42,469. (No model.)

To all whom it may concern:

Be it known that I, JOHN CALDWELL, a citizen of the United States, residing at Minneapolis, in the county of Hennepin and State 5 of Minnesota, have invented certain new and useful Improvements in Leather-Stretching Devices, of which the following is a specification.

My invention relates to apparatus for stretching skins or hides, and especially to the means employed in stretching the divisions of leather commonly known as "sides," "backs," &c., for use in the manufacture of belting. The common practice in the preparation of leather 10 for belting is to sever the hides transversely at the shoulder, trim the sides to straighten the edges, and cut the butts longitudinally into sides and backs or other divisions of desired widths, but leaving the rump ends of 15 irregular shape. For holding such divisions during the operation of stretching the common practice is to clamp the ends to the proper members of a stretching-machine, and in order to prevent the slipping of the leather 20 in the clamps under strong tension it is found necessary to provide the contact-surfaces of the clamps with ribs or other irregularities, with the result of producing corresponding creases or irregularities in the clamped portions 25 of the leather, which portions are generally unfit for use in the manufacture of belting and are cut off as waste. When the rump or other irregular ends are thus clamped across the body of the leather back of the 30 irregularities, considerable valuable leather becomes waste.

It is the principal object of the present invention to provide simple devices for securing the leather in a way that will avoid the 40 formation of objectionable creases in it, lessen the proportion of waste material, and effect a more desirable stretching of all parts of the leather. Such devices are illustrated in the accompanying drawings, in which—

Figure 1 is a vertical longitudinal sectional view of a leather-stretching apparatus embodying my improvements. Fig. 2 is a plan view of the front or right-hand portion of the apparatus shown in Fig. 1, and Figs. 3 and 45 50 are respectively plan and vertical sectional

views of one of the devices for engaging and holding the leather.

In such drawings the frame for supporting the leather-holding devices is composed of side pieces 1, cross-bars 2, and diagonal braces 55 3. The fixed and sliding heads to which the ends of the leather are secured are designated by A and B, respectively, and the head B is provided with suitable lateral extensions in ways 4, formed in the side bars 1, abutting the 60 ends of the movements. In use the frame is preferably placed on a table or support 5, with the ends of the side bars 1 abutting the ends of the frame 6, that supports the operating mechanism. The latter may consist of 65 any of the usual means employed in such machines—as, for instance, gears for operating a screw that is revolubly connected to a cross-head and rods 7, carried by the latter and provided with hooks 8 for connecting 70 them to eyes 9, provided on the sliding head. The operation of the screw in either direction and its stoppage when desired should be under the control of an operator by means of a lever, hand-wheel, or other well-known device, (not shown,) so that the degree of the 75 stretching of the leather may be regulated at will by the operator.

The heads A and B may consist of boards or wooden bodies 10, held at front and rear 80 between angular clamping-plates 11 and 12. A bolt 14, extending through the frame sides into or through the head A, holds it firmly in place in the frame.

Dogs 15, pivoted to ears on the plates 12 of 85 the sliding head B, engage teeth on bars 16, attached to the frame sides 1, for preventing backward movement of the head when the tension of the draft-rods 7 is relaxed.

For securing the straight end of a side C or 90 other division of a hide to one of the stretcher-heads (preferably to the slideable head B) the head selected for the purpose is provided with a row of tines or pins 17 on a bar or plate 18, that is secured on the top of the head, the row 95 of tines extending across the head from side to side at right angles to the direction of movement of the slideable head. The straight end of the leather is laid on the tines so that they will penetrate its margin close to the 100

edge, and it is then pounded with a mallet or other tool to force the tines through it.

For securing the rump end of the leather to the other stretcher-head I employ a series 5 of longitudinally and laterally adjustable independent holders, each of which is pivotally supported and is adapted to engage only a short portion of the leather margin. These holding devices may consist, as illustrated, 10 of a plate or body 19, having a row of tines or pointed pins 20 for engaging the leather and having in its rear portion a horizontal slot 21 for receiving the end of a bar or coupling device 22 and having also curved slots 15 23 or openings in its upper and lower walls to receive and guide a pin or roller 24, that projects from the upper and lower surfaces of the bar 22. A pivotal connection is thus formed between the body 19 and the bar 22, 20 whereby either may be turned in horizontal direction to any desired inclination relative to the other. The lateral extension of the slots 23 or openings enables a corresponding lateral adjustment of the points of such pivotal connection to be effected. 25

The bar or shank 22 has a series of vertical holes 25, and the head A is provided with pins or studs 26, arranged in a row on a plate 27, extending across it at right angles to the 30 frame sides 1, and the bar is thus enabled to be adjusted both laterally and longitudinally and then secured to the head by engaging one of the studs on the latter in one of the holes in the bar. The coupling-bar, therefore, is 35 pivotally as well as adjustably connected to both the leather-holder and the stretcher-head.

In applying the holders to the irregular end of a piece of leather the row of tines of each 40 holder is set substantially in line with the edge of the margin of leather it is to engage, and tines are then driven through the leather, and when all of the holders have been thus secured all of the coupling-bars may be adjusted laterally to positions substantially parallel with the direction of movement of the sliding head, (indicated by the arrow *a* in Fig. 2,) and when so adjusted they may be connected to the stretcher-head by engaging them with 45 the pins 26.

In conducting the operation of engaging and stretching the leather it is desirable to stretch the softer and more yielding portions to a greater extent than the harder and less 55 yielding portions. To effect such result, it is only necessary to connect and operate different holders of the series in proper sequence—that is, the holders for the softest and most yielding portion should be first connected and 60 that portion given an initial stretching before other holders are put to work and the other portions of varying consistency successively engaged and stretched. As illustrated in Fig. 2, the holders shown as in engagement with the shorter portions of leather, which are portions nearest the sides of the 65 hide and softer, more yielding, and capable

of being stretched to a greater extent without injury to the fiber than adjoining or other portions, may be first put in service and the 70 side portion of leather stretched until it is of about the same tenacity or ability to resist stress as the portion that is contiguous to it, and the other holders may then be put to work in proper sequence to stretch different longitudinal sections of the leather to different degrees, each successive holder stretching to a less extent the portion it engages than preceding holders stretch that which they engage. 80

It is found in practice that by the use of a series of holders each of which is adapted to engage only a relatively short marginal portion of the irregular end of a body of leather the leather can be stretched to a greater extent and to a more uniform condition than by the means commonly employed in leather-stretching machines, that it is thereby better fitted for use in the manufacture of belting, and that a saving results therefrom 85 in the preservation as part of the body of leather of considerable portions of the irregular ends, which when the usual means for engaging them are employed are rendered unfit for belting and are cut off and become 90 waste of little value.

This application is a division of my pending application, No. 1,424, filed January 25, 1900, and the patentable subject-matter herein shown and not claimed herein is reserved 95 to be claimed in said earlier application, and the subject-matter of invention herein disclosed and not claimed relative to the means for varying the point of pivotal connection of the holder to the coupling device conformably 100 to the direction of tension of the leather is reserved to be claimed in my pending application, No. 10,128, filed March 26, 1900.

Having described my invention, what I claim is—

1. In a leather-stretching machine, the combination with a stretcher-head, of a series of independent leather-holders adjustable laterally and longitudinally thereof, and a corresponding series of coupling devices having laterally-adjustable pivotal connection with the holders adapting the latter to swing freely under tension, and means for independently pivoting each of said coupling devices to the stretcher-head, substantially as set forth. 115

2. In a leather-stretching machine, the combination with a stretcher-head, of a series of leather-holders adapted to engage marginal portions of leather at different inclinations to the direction of tension upon it, coupling devices having free pivotal connection with the holders for attaching them to a member of the stretching mechanism, means for lateral variation of the points of such pivotal connection corresponding with the varying inclinations of the holders, and means for adjustably and pivotally connecting such coupling devices to the stretcher-head, substantially as set forth. 120 130

3. In a leather-stretching machine, the combination with a stretcher-head, of a series of leather-holders adapted to engage marginal portions of leather at different inclinations to the direction of tension upon it, coupling devices having free pivotal connection with the holders for attaching them to a member of the stretching mechanism, means for lateral variation of the points of such pivotal connection corresponding with the varying inclinations of the holders, and means for independently and successively pivotally connecting such coupling devices to the stretching mechanism, substantially as set forth. 25
- 5 4. The combination with a leather-holder and a stretcher-head, of a coupling-bar having a laterally-adjustable pivotal connection with the holder adapted to permit the holder to swing freely under tension, and means for 30
- 10 adjustably and pivotally connecting such bar to said head, substantially as set forth. 20
- 15 5. The combination with a stretcher-head, of a leather-holder having means for the lat- 35
- erally-adjustable pivotal connection of a coupling device adapted to permit free swinging movement of the holder under tension, a coupling-bar, and means for adjustably and pivotally connecting such bar to the leather-holder and to the stretcher-head, substantially as set forth. 40
- 30 6. A leather-holder for a stretching mechanism, consisting of a body provided with means for engaging the leather and having in rear of the leather-engaging means a slot concave in the direction of the latter, a coupling-bar adapted to engage in said slot and thereby pivotally connect said body to said bar, and means for adjustably and pivotally connecting the coupling-bar to the stretching mechanism. 45

In testimony whereof I have hereunto set my hand this 4th day of January, 1901.

JOHN CALDWELL.

In presence of—

P. H. GUNCKEL,
A. L. WHELAN.
